REFRIGERATOR DOOR OR LID

Clare H. Kafer, Palmyra, Mich., assignor to
Revco, Inc., Deerfield, Mich.

Application October 27, 1948, Serial No. 56,725

2 Claims. (Cl. 20—35)

1

This invention relates to a movable cover member, such as a door or lid, which is particularly applicable to refrigerated cabinets, and it is particularly concerned with a closure member having a gasket to seal the joint between the door and the box opening, together with cooperating means to retain the door in true alignment.

It has heretofore been proposed, and it has become a common practice in the art, to form door or lid members for refrigerated cabinets as shallow sheet metal pans in which insulating material is placed to prevent heat losses, and to close the open inner face of the pan by a plate or liner. It is also conventional practice to place strips of rubber or like resilient material along the inner edges of the door, so that, upon closing the door against the casing edges of the cabinet, a seal will be provided to prevent leakage of air around the joint. Problems have been presented, however, due to difficulty in providing a gasket which effectively seals the door around its entire perimeter. Other problems are involved in retaining the door in a square or true shape, as the door pan tends to warp out of shape, and correctives in the form of reinforcing frames have unduly increased both weight and cost.

According to the present invention, there is provided a cabinet closure having a continuous marginal flange to which a continuous gasket element is applied, which gasket is retained in tight engagement at all points by means of sealing clips and anchors. A practically perfect seal is thereby obtained against the cabinet face, and also between the interior and exterior portions of the door, to prevent heat exchange and moisture seepage.

The means employed for sealing the gasket to the door, especially at its corners, is moreover so formed that it may be utilized as a member cooperating to hold the door pan in its intended square or true shape, thus overcoming warping or distorting forces which would tend to separate the gasket from the door and thereby adversely affect its utility.

Other and further objects of the invention, and the advantages to be derived from the practice thereof, will become apparent from the following detailed description of a preferred embodiment, illustrated in the accompanying drawings, wherein:

Fig. 1 is a front elevation of a door, particularly adapted as a lid for a top opening cabinet, such as a deep freezer or food storage chest;

Fig. 2 is a bottom plan of the door;

Fig. 3 is a fragmentary side elevation of the door;

Fig. 4 is a fragmentary bottom view, on an enlarged scale, of the door shown in Figs. 1 and 2, with portions at several corners removed or broken away at different elevations, in order to show the details of construction and assembly;

Figs. 5 and 6 are fragmentary sections respectively taken on the lines 5—5 and 6—6 of Fig. 3;

Fig. 7 is a perspective of a corner gusset and gasket retaining plate; and,

Fig. 8 is a perspective of a tie rod retaining member.

The door shown in Figs. 1, 2, and 3 comprises a formed sheet of metal having a top or front 14 and angularly disposed sides 12 to provide a shallow rectangular pan. A latch 13 may be positioned along the front edge, and hinges 14 along the opposite side. The open face of the pan, which constitutes the inside of the door, is covered by a liner 15, and the perimeter of the pan and the liner are covered by a continuous gasket 16 of rubber or other resilient material, adapted to seal the joint between the door and the cabinet to which it is applied. The instant door is also shown as having an electric light casing 17 on the liner 15, whose service cord 18 leads through a switch 19 which is open when the door is shut, and closed when the door is open. The space within the pan is adapted to receive any suitable insulating material, so as to minimize heat transfer between the interior of the cabinet and the outside air. Doors of this nature are adapted to be used as horizontal lids for food storage chests, or as vertically mounted doors on the customary domestic refrigerator cabinets.

Referring next to Figs. 4, 5, and 6, the side walls 12 of the door pan are bent to provide relatively wide inwardly projecting flanges 21 along the perimeter and between the door corners, and relatively narrow inwardly projecting flanges 22 at the corners whose inner edges are curved to follow the contour of the pan corners. The wide flanges 21 are stopped a slight distance from the points where the curved pan corners merge into the straight sides 12, to provide sector-shaped cut away portions 23, as will be clearly apparent from the lower left corner view in Fig. 4. Cutting away the corners, and employing a narrow flange 22, facilitates the formation of the pan without the development of unsightly wrinkles in the metal, which would detract from the appearance of the door.

Each corner sector 23 receives a gusset plate or bracket 25, the specific formation of which is clearly shown in Fig. 7. The plate consists of a sheet metal stamping having an upper step or

ledge 26 whose outer edge is curved to follow the corner contour, and which merges through a riser 27 into a lower step or ledge 28 which is similarly curved. A second riser 29 merges into a bracket 31 having a substantially circular outer margin, and disposed substantially parallel to the steps 26 and 28. The bracket 31 is also formed with two slots 32 and 33, angularly disposed or out of parallelism with each other, and for a purpose which will presently appear.

The plate 25 is positioned over the sector 23 so that the extremities of the step 28 engage the ends of the adjacent wide flanges 21, while the step 26 is positioned above and is slightly spaced from the narrow corner flange 22 by the riser 27. This arrangement is shown particularly in the upper left corner in Fig. 4, and also in Fig. 5. From these views, it will also be seen that the bracket section 31 is disposed below the elevation of the flanges 21 and 22, and that it projects inwardly toward the diagonally opposite corner of the pan. Each plate 25 is secured to the flanges 21 by spot welding, as indicated by the reference numeral 34, thus integrating the assembly and increasing its over-all strength.

Diagonally disposed cross ties extend from the brackets 31 along the front edge 12 of the pan to the opposite corner along the rear edge, in order to square the door and retain it from distortion. It is, of course, practical to connect these straps to opposed brackets 31 when the door is fabricated, but it is preferred to include some means of adjustment and rectification after complete assembly, and therefore additional means are provided at the rear corners for this purpose.

The two cross tie members may take the form of thin, heat treated, sheet metal straps 35, 35a, each of which is connected to its associated bracket 31 at the front corner of the pan. At the front left corner, as viewed in Fig. 4, the strap 35 is bent or looped through the slot 32 and is secured on itself by crimping a metal clamp 36 around the overlapping portions. At the front right corner, wherein the plate 25 is shown in dotted lines beneath the liner 15, the companion strap 35a is similarly connected, except that its end is bent through the slot 33, instead of the slot 32. It will be seen from comparison of the two corners that, in each case, the strap is passed through that slot which is normal to the diagonal, and the two slots are so positioned that one or the other becomes normal to the diagonal as the plate is moved from one corner to the other. Accordingly, in each instance, the bight of the strap engages its associated slot over its entire surface, and shearing forces tending to cut the strap at the bight are thereby eliminated.

The provision of the two slots, respectively normal to the diagonals at the adjacent corners, enables the plates 25 to be assembled in any corner without prior selection and matching. The angularity between the two slots is so chosen, of course, as to satisfy the criterion of normality, and this angularity will depend upon the ratio of the long and short sides of the pan, which in turn determines the angle included between either side and the diagonal. It may be shown, for example, that with one slot disposed normal to its diagonal, then the other slot should be positioned at an angle thereto equal to $(90^\circ - 2x)$, where x is the angle between the diagonal and the long side of the rectangular pan.

The opposite ends of the diagonal ties 35, 35a are secured in their respective lower right and

left corners by anchor members 41, such as is shown in Figs. 4, 5, and 8. The anchor consists of a sheet metal stamping having an inwardly extending flange 42, corrugated or beaded with ribs 43 to increase its resistance to distortion, and formed with a slot 44 adapted to receive the end of the strap 35 or 35a which is bent through the slot, and is secured with a clamp 36. The anchor further includes a depending flange 45, medially formed with an aperture to receive a headed nut 46, so positioned that the body of the nut projects toward the corner, while the head engages the flange on its inner side to prevent separation. A screw 47 of suitable length extends through an aperture 48 drilled at the corner, and it may obviously be drawn up to increase the tension on the associated strap, and thereby pull the sides 12 of the pan into right angled relation. If the pan should, during use, warp slightly out of true, it is a simple matter to increase or decrease the tension on one or both straps, thereby rectifying the misalignment.

The apertures 48 are drilled on lines coinciding with the longitudinal axes of the straps, or along the true diagonals, and the slot 44 is formed at right angles to the longitudinal axis of the nut 46. Accordingly, the bight of the strap passing through the slot 44 will engage over the entire surface, irrespective of which corner is referred to. Hence, it is unnecessary to form the anchors 41 with angularly disposed slots, and the correction for angular differences is made by proper location of the apertures 48.

After the pan has been equipped with the gussets, cross braces, and anchors, and has been squared, it is ready to receive the gasket 16, which has a generally rectilinear shape following the contour of the pan, and whose dimensions are only slightly less in length and width. The gasket 16 is continuous, and it may be molded from rubber or other suitable resilient material. It consists of a connector section 51 whose width is slightly less than that of the flange 21 or 22, and which section is directly laid on the flanges 21 and 22. A hinge section 52 disposed at the outer edge of the gasket merges into a half round section 53 overlying the section 51, and which may be made hollow if desired, to increase the resilience and sealing properties. The connector section 51 is securely retained on the flanges 21 by means of channel members 55, having lengths approximately equal to the distances between adjacent edges of the sectors 23, the arms of which respectively engage the inner surfaces of the flanges 21, and the surface of the connector 51 directly below the section 53.

After being positioned in a rather loose manner, in order to facilitate assembly, the arms of the clips 55 are forced together by applying a compressing or pinching tool of any suitable type, thereby locking the gasket to the flanges 21 and practically covering and obscuring the connector section 51 of the gasket. Those portions of the section 51 not covered by the clips 55 are located, of course, at the pan corners, and these pass under the steps 26 of the gussets 25, entering the clearance gaps provided by the risers 27. In order to accommodate the connector section 51 to the difference in width of the flanges 21 and 22, the corner portions may be cut away, as is shown in Fig. 5. These corner portions are therefore enclosed between the flanges 22 and the steps 26, and, after assembly, the steps 26 are compressed with a suitable tool against the adjacent sections 51,

thereby securely connecting the gasket at the corners, as well as along the edges 12.

It will thus be seen that the gasket 16 is sealed to the door pan throughout its entire perimeter, including the curved corner portions, and that it cannot be readily pried away at any point. Such substantially continuous sealing and joining is highly advantageous to prevent entrance of moisture into the interior of the pan, where its presence could generate odors and corrosion. It is further to be noted that the result is obtained with a simple and inexpensive construction.

After the gasket 16 has been assembled, the liner 15 is inserted to complete the structure. The liner is in the form of a sheet of suitable material, such as plastic or the like, and it is assembled by pulling back the sealing section 53 of the gasket 16 about the hinge section 52. The liner 15 is retained against the outer arm of the channels 55 by the pressure exerted by the sealing section 53, and which is sufficient to discourage efforts of unskilled users to dislodge it. The engagement of the section 53 is sufficient to secure the liner 15 with some freedom of movement parallel to the flanges 21 and 22, to compensate for temperature changes, the smooth surfaces between the liner and channels 55 reducing the total friction to enable such movement to take place. If desired, however, additional securing means may be provided through apertures 57 (Fig. 6), disposed around the margins of the liner.

It will be seen that by providing the stepped corner gussets 25, the pan corners are reinforced, and means are provided to seal the gasket 16 to the door and to retain the door in alignment. It will also be noticed that provision has been made to locate the cross tie members 35 and 35a on true diagonals, thereby framing the door in such manner as to insure maximum rigidity. It will, of course, be understood that while the invention has been described with respect to a single embodiment, it is susceptible of numerous modifications and variations without departure from its principles, and its scope as set forth in the following claims.

I claim:

1. A refrigerator door comprising a pan having a front, depending sides, and inwardly projecting flanges extending from said sides around the perimeter of the door, said flanges at the corners of the door being of less width than the flanges between said corners, gusset plates secured to the wider flanges adjacent said cor-

ners, said gusset plates having elevated steps overlying the flanges at the corners and following the contour thereof, a continuous gasket having a connector section positioned on said flanges, the portions of the connector section at said corners underlying said elevated steps, channel shaped clamps positioned along the wider flanges over substantially the entire distance between the corners and engaging over the connector section therebetween, said elevated steps and clamps being compressed against the connector section to retain said gasket in substantially continuous engagement with said flanges around the perimeter of the door, and a liner positioned over said plates and clamps to close the cavity formed by said depending sides.

2. A refrigerator door comprising a rectilinear sheet metal pan having a front, depending sides, and inwardly projecting flanges extending from the sides around the perimeter of the pan, said pan and sides having curved corners, the inwardly projecting flanges being partially cut away at said corners, a continuous gasket positioned on said flanges around the perimeter of the pan and having curved corner portions conforming to the contour of the pan corners, gusset plates secured to the inwardly projecting flanges at said corners, said plates having raised step portions overlying the flanges at said corners and said steps having rim portions also curved to conform to the contour of the pan and gasket corners, said gasket corners being positioned under said steps and retained thereby, the curved rims of the steps engaging the curved corner portions of the gasket thereby to retain the corner portions of the gasket in perimetral alignment with the pan, and additional means between the corners of the pan and gasket to retain said gasket against said flanges.

CLARE H. KAFER.
